UNITED STATES PATENT OFFICE.

HORACE H. HASTINGS, OF TORONTO, ONTARIO, CANADA.

HYDROCARBON-BURNER.

1,199,177.

Specification of Letters Patent. Patented Sept. 26, 1916.

Application filed August 23, 1915. Serial No. 46,881.

To all whom it may concern:

Be it known that I, HORACE H. HASTINGS, a subject of the King of Great Britain, residing at Toronto, in the county of York, Province of Ontario, and Dominion of Canada, have invented certain new and useful Improvements in Hydrocarbon-Burners, of which the following is a specification.

My invention relates to improvements in hydrocarbon burners.

One of the objects of my invention is to provide a burner especially designed for use in cooking stoves or ranges, and in heaters, but which is so constructed that it may be used for other purposes where a liquid-fuel burner may be employed.

Another object of my invention is the provision of a burner of this class of simple and inexpensive construction which can be easily applied within any common form of cooking stove or range and which is provided with means for regulating the burner to conform to the draft conditions of the stove or range.

Another object of my invention is to so construct the burner that the fuel supply jets or nozzles will be evenly supplied with fuel and so that the fuel carried to these jets or nozzles is subjected to hot air or the products of combustion and therefor gasify more readily.

A still further object is to provide novel means for regulating the air supplied to the jets or nozzles and so that the air, and liquid or gasified liquid, as the case may be, can be proportionately fed to the burner for best results.

Further objects are to construct a burner of this type capable of giving perfect combustion with crude oil, and to so construct the burner that an even flame from each nozzle is obtained, even though the burner is not set level.

Still further objects are the production of a burner equipped with means for consuming all carbon and other unconsumed products of combustion within the fireplace, and to provide liquid fuel distributors for the nozzles, also to otherwise improve on burners of this type now in use.

With these objects in view, the invention consists in the novel features of construction and in the arrangement and combination of parts to be hereinafter described and more particularly pointed out in the subjoined claims.

Reference being had to the accompanying drawings, I will now describe the embodiment of my invention illustrated; it being understood that my invention is not limited to the exact details of construction shown therein; but that they may be varied to adapt the invention for various purposes a burner of this class is capable of use.

Figure 1 is a perspective view of the complete burner. Fig. 2 is a central longitudinal section through the same. Fig. 3 is a detached perspective view of one of the fuel distributors. Fig. 4 is a detached perspective view of one of the regulating gates or valves by means of which the air supply to the fuel nozzles is regulated. Fig. 5 is a transverse section taken on line *a*—*a*, Fig. 2. Fig. 6 is a plan view of one-half of the base or bottom member of the burner. Fig. 7 is a bottom plan view of the base or bottom member. Fig. 8 is an inverted view of the hood or top member of the burner, the distributing pipes for hot air or products of combustion being broken away. Fig. 9 is a longitudinal section through a cooking stove or range having my improved burner applied thereto. Fig. 10 is an enlarged cross section of the adjustable legs or supports for the burner, the same being taken on line *b*—*b*, Fig. 9.

Referring now to the drawings in detail, like numerals of reference indicate like parts in the several figures.

The reference numeral 11 designates a cooking stove or range, 12 the fire pot thereof, 13 the grate of the fire pot, and 14 the lids of the stove or range.

15 designates the burner having connection with a liquid-fuel reservoir 16 by means of a feed or supply pipe 17 leading to the burner, as will appear hereinafter, said feed or supply pipe having a valve 18 to control the flow of the liquid-fuel to the burner.

The burner comprises two main parts 19, 20, the part 19 being a base or bottom member and 20 the hood or top member. The bottom member has a central chamber or bowl 21, from the upper end of which extends an outstanding web or plate 22, the plate extending a considerable distance from opposite ends of the bowl or chamber 21 and being provided with air openings 23. The top of this base plate has retainer flanges 24 around three sides of each of said openings. Extending upwardly from the bottom of said chamber or bowl 21 are a pair of cones

25, one arranged at each side of a plane extending centrally and transversely through the bowl. The bottom and sides of the chamber or bowl are cored out, as at 26, to 5 provide an air chamber, and the bottom wall of this air chamber is provided with air openings 27 adapted to be opened to the desired extent, or entirely closed, by a slide valve 28, said valve having corresponding 10 openings 29 adapted to be moved into registration with the openings 27, or partially into registration, as may be desired, for feeding the air into the chamber 26. This valve is also provided with an elongated 15 opening 30 through which the feed or supply pipe 17 is passed, the end of said supply pipe being threaded into the bottom wall of the base or bottom member. The cones 25 are cored out, as at 31, and the hollow interior thereof may be said to be continuations of the air chamber 26.

Projecting from the upper end of each cone is a nozzle 32 which extends down through the cone, a central opening or passage 33 being arranged in each nozzle, forming a feed passage for the liquid fuel. These passages converge and terminate in an enlargement 35 into which the liquid fuel is fed from the feed or supply pipe 17. 30 Each cone has a series of air openings 36 formed in its upper wall and a series of air openings 73 in its peripheral wall. These openings are at all times in communication with the hollow interior of the cones and 35 consequently with the air chamber 26.

Fitting for rotatable movement on the cones are hollow conical gates or valves 37, each being provided with a handle 38 adapted to extend outwardly over the base plate 40 at one side thereof. Said plate has at opposite sides two pairs of indicating marks, and over each pair, one of the handles is arranged for movement. The upper wall of each of these hollow conical gates or valves 45 is provided with a series of air openings 39 corresponding in size and number to the air openings 36 in the top walls of the hollow cones, while the peripheral wall of each gate or valve has a series of air openings 74 50 corresponding in size and number to the openings 73 in the peripheral walls of the cones. When rotating said valves by means of the handles 38 the openings in said valves may be brought into registration with said 55 openings 36 and 73, or partly so, or may be moved to positions between said openings so that the air is entirely shut off at these points.

I have shown the initial "O" at 40 to indicate that the air openings 36 in the hollow cones are opened by the valves 37 when the handles 38 are moved over said indications. I have shown the initial "S" at 41 to indicate that the openings 36 of said hollow 65 cones are shut or closed when the handles

38 are moved over said initials. It is of course apparent that when the handles are between the indications "O" and "S," the openings 36 and 73 are partly opened. These indications, as stated, are arranged at opposite sides of the base plate 22 so that the valves 37 may be positioned over the cones with the handles thereof extending to either one side or the other, as may be found most convenient. In order that these valves 75 may be seated on the cones they are provided with a central opening 42 through which the projecting ends of the nozzles 32 extend.

43 designates a fuel distributor which is 80 in the form of a hollow hub or sleeve 44 from which a plurality of arms 45 radiate, said arms being provided with grooves 46 on their upper sides and being inclined downwardly toward their outer ends. 85 These distributors are positioned over the projecting ends of the nozzles with the lower edge of the hub or sleeve 44 bearing against the upper surface of the conical valves 37.

Around the hollow cones 25 I arrange absorbent material 47, preferably asbestos wicking, the purpose of which is to provide a substance in the bottom of the bowl or chamber 20 capable of absorbing liquid-fuel. The air chamber 26 is provided centrally between its ends at opposite sides of the bowl or chamber 21 with two tubes or flues 48, which have preferably a cylindrical interior. The lower ends of said 100 tubes open into the air chamber and the upper ends thereof are open and provided with flaring seats 49. The side walls of the chamber or bowl 21 are provided with air openings 75 which place the upper end of 105 the air chamber 26 in direct communication with the chamber or bowl.

The hood or top member comprises a hollow elongated central portion 50, the side walls of which taper downwardly, and 110 at opposite ends of said central portion are arranged a pair of air intakes 51 open at their lower ends and having communication with the central portion, as at 52. The air intakes and hollow central portion may be 115 termed an "air chamber" which opens through the air intakes 51 into the fireplace. For this purpose the intakes 51 extend downwardly beneath the bottom wall of the central portion and rest upon the 120 ends of the base plate 22, the openings in the lower ends of said intakes being of a size equaling the air openings 23 in said plate and registering therewith, said intakes fitting within the retainer flanges 125 24. The bottom wall of the central portion 50 has a pair of openings 53 which are preferably arranged directly above the fuel nozzles. These openings are shouldered, as at 54, so that when required, perforated 130

disks 55 may be inserted in the openings and seated against said shoulders from the interior of the top member. The hollow central portion 50 has a pair of flues 56 arranged midlength and at opposite sides thereof, and openings 57 are formed in the side walls of said central portion to serve as means of communication between the interior of said central portion and said flues. 10 These flues are vertically-disposed with the lower ends 58 projecting beneath the bottom of said central portion, the lower extremities of said flues being tapered, as at 59, and seated into the flaring upper ends 15 of the flues 48. The flues 56 may therefore be considered as continuations of the flues 48 when the top member is positioned on the bottom member.

The central portion of the hood or top member is situated directly over the bowl or chamber 21 of the base or bottom member, and in order that the flame may have free escape from said bottom member the central portion of said hood or top member 25 is made somewhat narrower than said bottom member. By flaring the walls of the central portion of said hood or top member, the flame is directed outwardly against the sides of the fireplace. The side walls of 30 the central portion 50 of said hood or top member are provided with numerous hot-air escape perforations 60.

I have also provided an auxiliary hot-air supply adapted to commingle with the 35 flames of the burner after entering the fireplace. This auxiliary air supply comprises longitudinally-disposed perforated pipes 61 arranged at opposite sides of the hood or top member near its upper end, the opposite 40 ends of said pipes being capped, as at 62, and the pipes having connection with the interior of the hood or top member by means of pipes 63 threaded into the side walls of said top member and into T-fittings 45 64 in the perforated pipes 61. These perforated pipes are arranged lengthwise of the burner and extend approximately from one end thereof to the other.

The burner is supported by means of 50 adjustable supports or legs 65 which rest upon the grate 13, these supports or legs being of considerable width so that their upper ends engage the base plate 22 at opposite sides of the air openings 23 formed 55 therein. They are formed of two members 66, 67, lying in contact and having their contacting faces roughened or corrugated, as at 68, the member 67 having a bolt hole 69 formed therein, while member 66 is provided with a vertically-disposed slot 70. A bolt 71 is passed through said bolt hole and slot and a thumb nut 72 threaded onto the bolt for clamping the two members firmly together, the slot 70 of each support or leg 65 permitting the latter to be shortened or

lengthened so as to support the burner in the desired position with reference to the top of the stove.

When the valve 18 of the feed or supply pipe is opened the liquid-fuel rushes up into 70 the burner and through the nozzles 32. The fuel escaping from the upper ends of the nozzles enters the grooves 46 of the radial arms 45 of the distributors and is delivered by said distributors into the bowl 21 and 75 onto the asbestos wicking or other absorbent material 47 in said bowl. The liquid-fuel thus accumulated in the bowl or chamber is ignited, inducing a draft through each of the end air intakes 51, toward the nozzles by way of the openings 53, where it meets the upwardly moving liquid-fuel at the exits of the nozzles and causes it to be distributed. The flame from the burning fuel in the bowl ignites the liquid-fuel 80 issuing from the nozzles and also heats the nozzles so that the liquid-fuel moving upward in the nozzles becomes gasified or vaporized. After formation and ignition of the gas or vapor has been established the 85 proper delivery of fuel to the nozzle may be controlled by the valve 18 in the feed or supply pipe.

The cones 25 become heated and the air in the air chamber 26 passes up into said cones and escapes through the openings 36 and 73 therein and the registering openings 39 and 74 of the conical valves 37, provided said valves are adjusted to bring the openings therein into registration with the openings in said cones. The heated air from the air chamber 26 also enters the bowl 21 through the openings 75 and feeds the flame. 95

The air from the fireplace enters the air 105 intakes at the ends of the hood or top member, and from these intakes it enters the hollow central portion of said hood or top member. This air, in addition to escaping through the openings 53, escapes through 110 the numerous perforations 60 in the side walls of the hood or top member; also through the openings 57 leading to the side flues 56 of the hood or top member. From the latter the air is fed through the flues 115 48 into the air chamber 26. The air passing through the hollow hood or top member becomes thoroughly heated and also escapes through the pipes 63 and enters the perforated pipes 61 at the sides of the hood 120 or top member.

The flames from the ignited fuel pass upwardly through the spaces 76 between the base or bottom member and the central portion of the hood or top member and are 125 drawn in all directions within the fireplace, thus heating the air within the fireplace so that after the burner is ignited for a few moments the heated air or products of combustion enters the hollow hood or top 130

member through the openings 23 in the base plate 22 and is directed downwardly through the flues 56 and 48 into the air chamber 26 and into the hollow cones 25, being further heated by radiation from said cones. This heated air also escapes through the perforations in the side walls of the hood or top member and comes in contact with the flame passing upwardly along said hood or top member, thus assuring perfect combustion. The flames passing upwardly a distance from the hood or top member are supplied with the heated air or products of combustion through the perforated pipes 61, which are spaced a distance from the side walls of said hood or top member so that currents of hot air or the products of combustion from the fireplace which enter the hood or top member are caused to combine with the flames and any unconsumed products of combustion ignited.

The heated air surrounding the fuel nozzles and escaping from the openings in the cones 25 acts to vaporize the fuel, resulting in a better combustion and an economical use of the fuel. The distributor 43 also assures economical use of the fuel, since it distributes the same over an extended surface and assures a hot flame of considerable area. It also causes the flame to spread and when escaping from the burner it is carried to all parts of the fireplace above the base member of the burner.

The currents of air moving downward through the openings 53 and onto the nozzles and distributor, act against the fuel and cause it to travel outwardly along the arms 45 of the distributor, thus spreading the flames which are supplied with heated air or products of combustion fed to it through the openings 36, 73 and 75, said heated air or products of combustion being drawn into the burner from the fireplace, which latter is thoroughly heated after the burner is lighted for a short period of time.

By arranging the burners side by side and in close proximity to each other, the flames issuing therefrom are of equal size or extend over equal areas, even though the burner is not positioned perfectly level, this being due to the closely positioned nozzles 32 which assure an even feed of the fuel to the nozzles.

When the stove is provided with poor draft, the slide valve 28 may be adjusted to bring the openings therein into registration with the air openings 27 in the bottom of the air chamber 26, thus permitting the hot air or products of combustion from the fireplace to enter the air chamber 26 directly. By bringing the nozzles or fuel passages together at the bottom of the burner, a single feed or supply pipe may be used, thus dispensing with at least one supply pipe and a valve to regulate the same.

When it is found that the draft of the stove is too great and would tend to check the feed of the liquid-fuel, the perforated disks 55, above described, are placed within said openings. This breaks up the air currents and allows the proper flow or passage of fuel over the nozzles and distributor.

When it is found that the mixture is too rich to obtain best results, the hollow conical valves 37 may be rotated to supply heated air to the nozzles.

Having thus described my invention, what I claim is,

1. A hydrocarbon burner comprising an upstanding cone, a nozzle projecting from the upper end of said cone, and a distributor applied to the projecting end of said nozzle and comprising a hub and radial arms having grooves inclined outwardly to distribute the fuel.

2. A hydrocarbon burner comprising a base having a bowl, an upstanding hollow cone having openings at its upper end, means admitting air to said hollow cone, a nozzle extending through said cone and projecting from the upper end thereof, and means for closing the openings of said cone or for opening the same to the extent desired to admit the air from the cone to the projecting end of said nozzle.

3. A hydrocarbon burner comprising a bowl, a pair of cones arranged side by side and extending upwardly in said bowl, absorbent material in said bowl around the bases of said cones, fuel passages passing through said cones and terminating in nozzles at the upper ends of said cones, said passages converging downwardly and merging into a single passage, and a fuel feed pipe connected to said single passage.

4. A hydrocarbon burner comprising a base having a plurality of hollow cones extending upwardly and provided with flat upper ends having openings therein, a hollow nozzle extending through each of said cones and projecting from the flat upper ends thereof, means for admitting heated air to said hollow nozzles, and means for opening or closing the openings of said cones to control the escape of heated air therefrom.

5. A hydrocarbon burner comprising a base having a bowl, a hot air chamber beneath said bowl, hollow cones extending upwardly from the bottom of said bowl and communicating with said hot air chamber, said cones each having a circular series of openings, nozzles extending through said cones and projecting from the upper ends thereof, said nozzles converging at their lower ends and having the passages thereof merging into a single passage, a fuel feed pipe connected to said single passage, and hollow conical valves fitting onto said cones and provided with openings adapted to reg-

ister with the openings of said cones, said valves being rotatable to close said openings.

6. A hydrocarbon burner comprising a base having a bowl, a hot air chamber beneath said bowl, hollow cones extending upwardly from the bottom of said bowl and communicating with said hot air chamber, said cones each having a circular series of openings at their upper ends, nozzles extending through said cones and projecting from the upper ends thereof, said nozzles converging at their lower ends and having the passages thereof merging into a single passage, a fuel feed pipe connected to said single passage, hollow conical valves fitting onto said cones and having openings registering with those of the cones, and a distributor applied to the upper ends of each of said nozzles and resting upon said conical valves, said distributor serving to deliver liquid-fuel into said bowl.

7. A hydrocarbon burner comprising a base having a bowl, a base plate extending outwardly from the upper end of said bowl, said base plate having two sets of indicating characters, a plurality of hollow cones extending upwardly from the bottom of said bowl and having flattened upper ends provided with air openings, means for delivering heated air into said cones, nozzles extending through said cones and projecting above the upper end of the latter, and hollow conical valves fitting onto said cones and having openings adapted to register with those of the cones, said valves having manipulating handles adapted to be moved over either of said indicating characters or to positions between the same.

8. A hydrocarbon burner comprising a base having a bowl, hollow cones extending upwardly from the bottom of said bowl and having flattened upper ends provided with openings, a hot air chamber in said base beneath said bowl communicating with the interior of said hollow cones and having air openings in one of its walls, a slide valve provided with openings to open or close said air openings, and nozzles extending through said cones and projecting from the upper ends thereof.

9. A hydrocarbon burner comprising a bottom member having upwardly-directed nozzles and a top member fitting onto said bottom member and providing flame escape spaces between the two, said top member being hollow and having air intakes admitting air thereto, the side walls of said top member being perforated to permit the escape of air to impinge against the flames extending upwardly along the sides of said top member.

10. A hydrocarbon burner comprising a bottom member having upwardly-directed nozzles, a top member having a hollow central portion and air intakes at its ends opening downwardly and being in communica-

tion with said hollow central portion, and a perforated air escape pipe arranged lengthwise along each side of said top member and having connection with the interior of the latter, said perforated pipes being spaced 70 from said top member.

11. The combination with a fireplace, of a hydrocarbon burner comprising a base having a bowl, a nozzle extending upwardly from said bowl, a top member supported by 75 said base and having a hollow central portion provided with an opening in its bottom directly above said nozzle and having end air intakes opening into the fireplace, the sides of said hollow central portion being 80 perforated, and a perforated pipe arranged lengthwise along each side of said top member and connected with the interior of said hollow central portion.

12. A hydrocarbon burner comprising a 85 base having a bowl, a base plate at the upper end of said bowl, an upstanding nozzle in said bowl, an air chamber in said base beneath said bowl, means for delivering air from said air chamber to and around the upper end of said nozzle, a top member fitting onto said base plate and having a hollow central portion directly over said nozzle and end air intakes opening into said hollow central portion, and a connection between said 95 hollow central portion and said air chamber.

13. A hydrocarbon burner comprising a base having a bowl, a nozzle extending upwardly in said bowl, an air chamber beneath said nozzle having upwardly-directed air 100 flues, a top member supported by said base and having a hollow central portion directly over said bowl and hollow end portions in communication with said central portion, and downwardly-directed flues at opposite 105 sides of said hollow central portion in communication with the latter and in communication with the flues of said air chamber.

14. A hydrocarbon burner comprising a base having a bowl, upwardly-directed fuel 110 nozzles in said bowl, a hot air chamber beneath said bowl, means for supplying heated air from said hot air chamber to the upper ends of said nozzles, air flues extending upwardly from said air chamber and having flared upper ends, a top member fitting onto said base and having a hollow central portion and air intakes at opposite ends of said central portion opening downwardly, and air flues at opposite sides of said central portion in communication with the latter, said air flues having tapered lower extremities fitting into the flared upper ends of said first-mentioned air flues.

15. A hydrocarbon burner comprising a base having an upstanding fuel nozzle, a top member having a hollow central portion and air intakes at opposite ends of said central portion in communication with the latter, 120 the bottom wall of said hollow central por-

tion having an opening therein directly above said nozzle, and a perforated disk applied to said opening.

16. A hydrocarbon burner comprising a bowl having chambered walls forming a hot air chamber beneath and around said bowl, cones extending upwardly from the bottom of said bowl, nozzles projecting from the upper ends of said cones, a fuel feed pipe connected to said nozzles, and means for directing air from said hot air chamber into said bowl.

17. A hydrocarbon burner comprising a bowl having chambered walls forming a hot air chamber, fuel nozzles within said bowl, and means of communication between said hot air chamber and said bowl, said means of communication opening into said bowl in a plane beneath the exits of said fuel nozzles.

20 18. A hydrocarbon burner comprising a base having a bowl, a hot air chamber beneath said bowl, hollow cones extending upwardly from the bottom of said bowl and communicating with said hot air chamber, each of said cones having openings in its peripheral wall, nozzles extending through said cones and projecting from the upper ends thereof, a fuel pipe connected to said

nozzles, and valves fitting onto said cones and provided with openings adapted to register with the openings of said cones, said valves being rotatable to close said openings.

19. A hydrocarbon burner comprising a base having a bowl, a hot air chamber extending around the sides of said bowl and in communication with the interior of the latter by means of air openings, hollow cones extending upwardly from the bottom of said bowl and being in communication with said hot air chamber, each of said cones having a circular series of openings in its peripheral wall, nozzles projecting from the upper ends of said cones, and rotatable valves fitting onto said cones and having openings corresponding with those of the cones.

20. A hydrocarbon burner comprising a bowl having nozzles extending upwardly therein, means for directing hot air against the upper ends of said nozzles in a direction opposite the flow of fuel in said nozzles, and means for directing hot air into the bowl in a plane beneath the exits of said nozzles.

In testimony whereof I affix my signature.

HORACE H. HASTINGS.
